KITE

Sam Kupperman and Dennis I. Kupperman, both of 4139 Main St., Skokie, Ill. 60603

Filed Jan. 21, 1971, Ser. No. 108,673

Term of patent 14 years

Int. Cl. D21—01

U.S. Cl. D34—15

FIG. 1 is a bottom plan view of a kite showing our design.

FIG. 2 is a top plan view thereof.

FIG. 3 is an enlarged view taken on line 3—3 of FIG. 6.

FIG. 4 is an end view taken on line 4—4 of FIG. 2.

FIG. 5 is a view taken on line 5—5 of FIG. 6, and

FIG. 6 is a view taken on line 6—6 of FIG. 3.

The frame and kite material have been omitted from FIGS. 5 and 6 for convenience of illustration.

We claim:

The ornamental design for a kite, as shown and described.
